UNITED STATES PATENT OFFICE.

NELSON E. WHIPPLE, OF WINDSOR, NEW YORK.

DRAFT CONTROL.

Application filed November 4, 1925. Serial No. 66,836.

This invention relates to heaters, such as furnaces, steam and hot water boilers and the like and has for an object the provision of means to automatically regulate the draft for the fire, so as to maintain a substantially even heat and thus economize in the consumption of fuel.

To this end, the invention provides means to automatically regulate the ash pit and feed door dampers, and the draft check of the flue, the said means acting to simultaneously open and close the draft check and the feed door damper and to close the ash pit damper when the feed door damper is open and vice versa.

With the above and other objects in view, the invention further includes the following novel features and details of construction, to be hereinafter more fully described, illustrated in the accompanying drawings and pointed out in the appended claim.

In the drawings:—

Figure 1 is a front elevation of a heater with the invention applied.

Figure 2 is a side view partly broken away.

Figure 3 is an enlarged sectional view taken substantially on the line 3—3 of Figure 1.

Figure 4 is a detail perspective view of the feed door lever.

Referring to the drawings in detail wherein like characters of reference denote corresponding parts, the reference character 10 indicates a heater which may be of any type and which includes a feed door 11 which is provided with a damper 12 and an ash pit door 13 having a damper 14.

Mounted upon the heater is a heat operated controlling member 15 which is operatively associated as indicated at 16 with a lever 17. This lever is mounted for pivotal movement as indicated at 18 and has one of its ends connected to a draft check damper 19 located within the smoke pipe or flue 20 of the heater, connection being effected by means of a link 21.

The lever 17 is connected to the damper 14 of the ash pit door by means of a chain 22 and as the temperature rises, the lever 17

will be moved pivotally to open the draft check and permit the damper 14 to close so as to reduce draft through the fire.

In addition, there is pivotally mounted upon the feed door as indicated at 23, a substantially L-shaped lever 24. One end of this lever is connected to the lever 17 by means of a chain 25, while its opposite end has a sliding pivotal connection 26 with the damper 12.

By the arrangement just described, when the check draft 19 is opened and the damper 14 closed, the lever 24 will be moved pivotally due to the length of its horizontal arm and will open the damper 12 so that the draft will be across the top of the fire bed and not through the fire. As the temperature lowers, the controlling member will operate the lever 17 to close the draft damper 19 and the damper 12 and open the damper 14.

The invention is susceptible of various changes in its form, proportions and minor details of construction and the right is herein reserved to make such changes as properly fall within the scope of the appended claim.

Having described the invention what is claimed is:—

In a heater having a damper in the fuel feed door, a damper in the ash pit door, a draft check in the smoke flue, a heat controlled operating member and a pivotally mounted lever associated with and operated by the operating member and connected with the draft check, means connecting the lever and ash pit door damper to open the latter when the draft check is closed and vice versa, a substantially L-shaped gravity operated lever pivotally mounted upon the feed door, means connecting one end of said lever to the feed door damper and means connecting the opposite end of said L-shaped lever with the heat controlled lever to close the feed door damper when the draft check is closed and open said feed door damper when the draft check is open.

In testimony whereof I affix my signature.

NELSON E. WHIPPLE.
